UNITED STATES PATENT OFFICE.

ALBERT N. WOODRUFF, OF WASHINGTON, DISTRICT OF COLUMBIA.

TYPE-BAR MECHANISM.

Application filed March 1, 1926. Serial No. 91,511.

My present invention relates generally to typewriters, and more particularly to type bar actions, my object being the provision of simple, strong and durable action which will, among other things, provide for a short light touch as well as for power where power is needed and speed of movement of the parts where speed and not power is the most to be desired.

10 In the accompanying drawing which illustrates my present invention,

Figure 1 is a side view of my improved action showing its practical application in more or less diagrammatic form,

15 Figure 2 is a detail perspective view of one of the type bars and the adjacent end of the intermediate or sub-lever, and

20 Figure 3 is a detail perspective view of a portion of one of the key levers and the adjacent end of the respective intermediate or sub-lever.

25 Referring now to these figures, my invention proposes a type bar action including a type bar 10 having lengthwise spaced type 30 11 and 12 adjacent to its free end and having its opposite end enlarged and apertured as at 13 for pivotal mounting upon a type bar supporting rod 14. The enlarged pivoted end of the type bar, the latter of 35 which is in practice substantially flat throughout, has gear teeth 15 for the major portion therearound which, as will be noted from Figs. 1 and 2, form a geared surface eccentric with respect to the pivot opening 40 13. In its normal position the type bar 10 extends forwardly approximately in a horizontal position with its free type carrying end resting for instance upon a type bar rest pad 16.

45 The type bar action proposed by my invention also includes a key lever 17 which may have at its forward end the usual angular upstanding extension 18 carrying one of the keys 19. This type bar is fulcrumed intermediate its ends and at a point nearer to its rear than its forward end, for instance upon a cross rod or other suitable bearing 20, and the rear end of the key lever which is slightly downturned as seen at 21, and 50 particularly shown in Figure 3, is provided with a laterally outstanding pin 22 loosely supporting a roller 23.

55 An intermediate or sub-lever 24 forms a direct connection between the key lever 17 and the type bar 10, and is disposed in an upright position with its lower end pivot-

ally supported by virtue of its pivot opening 25, upon a cross bar or other suitable bearing 26. Adjacent to its lower pivoted end, the intermediate or sub-lever 24 has a rearwardly projecting angular arm 27 terminating in a down turned nose 28, and the lower surface of which arm 27 is engaged by the roller 23 of the key lever.

60 At its upper end the intermediate or sub-lever 24 has a flared enlargement 29 upon the upper end of which is formed a rack 30 engaging the teeth 15 of the type bar 10, while the sub-lever 24 as a whole is controlled by a spring 31 which may in practice be anchored at its rear end 32 upon any suitable portion of the frame of a typewriter, and has its forward end engaging the intermediate or sub-lever between the ends of the latter and preferably at a point nearer to the lower end than the upper end.

65 In action, the intermediate or sub-lever 24 will be held in its rearmost position shown in full lines in Figure 1, by the tension of spring 31, and it is obvious from this that the spring serves to return the type bar 10 to its normal inactive position and hold the same in such position in its forward extension upon the rest pad shown 70 at 16 in Figure 1.

75 When pressure is applied to the key 19 of the key lever 17, however, the forward portion of this lever will be depressed and its rear end with roller 23 will be elevated. The latter in its bearing upwardly against the lower surface of the rearwardly angular arm 27 of the intermediate or sub-lever 24 will rock this lever upon its lower pivot 26 end in a forward direction to the dotted line position of Figure 1, whereby in the 80 course of such movement, engagement of rack 30 of the intermediate or sub-lever with the gear teeth 15 of the type bar 10 will force the latter to swing in a vertical plane upwardly from the rest pad 16 and 85 then downwardly against the platen 33.

90 Obviously this action may be included in the space having a comparatively short vertical dimension since the intermediate or sub-lever 24 may be of considerable length 105 and the type bars 10 normally rest in horizontal position.

95 It is obvious furthermore that the initial portion of the operative movement of the type bar is in an upward direction requiring 110 comparatively greater power than the second portion of its movement in a downward

direction against the platen. It is for this reason that the gear teeth 15 are arranged to form a surface eccentric with respect to the pivot of the type bar as plainly shown in Figs. 1 and 2 so that in the initial portion of its movement substantially greater power is applied to the type bar as compared to that applied thereto in the second portion of its movement or downward stroke, where power being unnecessary, is sacrificed to speed.

The connections proposed by my invention are simple and inexpensive, may be readily and cheaply manufactured, and easily and quickly assembled, and in addition to minimizing the number of necessary parts, my invention in providing for the direct connection of the key lever with the type bar by virtue of the single sub-lever, promotes great strength and durability and avoids the necessity of adjustment and careful fitting of the parts.

I claim:—

1. In a typewriter, a type bar pivotally supported adjacent to one end and having teeth at its pivoted end forming a gear sur-

face along a line eccentric with respect to the said pivot, a sub-lever pivotally mounted at its lower end and having an angular outstanding arm adjacent to its pivoted end, and a rack at its upper end engaging the teeth of the type bar, and a key lever fulcrumed intermediate its ends and having at its rear end a laterally projecting roller engaging the lower face of the angular arm of the sub-lever, as described.

2. In a typewriter, a type bar pivotally supported adjacent to one end and having teeth at its pivoted end arranged to form a gear eccentric with respect to the pivot thereof, a sub-lever pivotally mounted at its lower end and having a downwardly facing surface at one side of its pivot, said sub-lever having a rack formed upon its upper end and engaging the teeth of the type bar, and a key lever fulcrumed intermediate its ends and having means movably engaging the said lower surface of the sub-lever for swinging the lever when the key lever is actuated.

ALBERT N. WOODRUFF.
